UNITED STATES PATENT OFFICE.

HARRY L. WOOD, OF DOWAGIAC, MICHIGAN, ASSIGNEE TO PREMIER WARM AIR HEATER COMPANY, OF DOWAGIAC, MICHIGAN, A CORPORATION OF MICHIGAN.

FURNACE CONSTRUCTION.

1,412,989.

Specification of Letters Patent. Patented Apr. 18, 1922.

Application filed July 30, 1921. Serial No. 488,519.

To all whom it may concern:

Be it known that I, HARRY L. WOOD, a citizen of the United States of America, residing at Dowagiac, in the county of Cass 5 and State of Michigan, have invented certain new and useful Improvements in Furnace Construction, of which the following is a specification, reference being had therein to the accompanying drawings.

10 This invention relates to furnaces, and more particularly to furnaces having passages through which air flows, to be heated. The invention consists primarily in the employment of certain plates for connecting 15 inner and outer casing members of a furnace, which casing members form an air passage, and in the relation of said plates to the terminal plate for the fuel feed and ash-pit projections from the heater of the 20 furnace.

In the drawing:

Figure 1 is a vertical sectional view of the improved furnace, the plane of section being through the fuel feed and ash-pit 25 projections from the heater;

Figure 2 is a horizontal section on line 2—2 of Figure 1;

Figure 3 is a section on line 3—3 of Figure 2, showing a connection between the 30 feed mouth section of the furnace and an adjacent plate.

In these views, the reference character A designates a heater having the combustion chamber B and ash-pit C, and having projecting portions D and E, respectively having passages for fuel delivery to the combustion chamber and removal of ashes from the ash-pit. Said heater is positioned within inner and outer cylindrical casings F and 35 G, formed preferably of sheet metal and having gaps at the front of the furnace to accommodate said projecting portions of the heater. The outer casing G extends from top to bottom of the furnace, while 40 the inner casing F terminates slightly above the ash-pit level. The space between the casings F and G forms a passage for the downflow of air and an upflow passage is formed between the inner casing and the 45 heater A, such an arrangement being well known in the art. The gap at the front of the outer casing G is closed by a plate H having door openings I and J respectively 50 registering with the passages in the portions D and E, said member H forming a

terminal plate for said portions D and E. The lateral margins of the plate H are connected to the vertical edges of the gap in the inner casing F by a pair of vertically elongated plates K having at their inner 60 edges flanges K' projecting from each other and secured by bolts K² to the inner casing and having flanges K³ formed upon their opposing faces, engaged by the plate H. Said plates terminate at their lower ends 65 in registration with the lower edge of the casing F. The plates K are connected to the fuel feed projection D, as shown in Figure 3, lugs L being formed integrally and oppositely upon the member D, and 70 angular brackets M carried respectively by the plates K being bolted to said lugs as indicated at N. Preferably the brackets M are adapted for a limited vertical adjustment upon the plates K by slotting said 75 brackets, as indicated at O, to engage the securing bolts P. By forming the plates K separately from the casings F and G and from the plate H, said plates may be rolled or cast of the necessary thickness to exercise 80 their spacing and partitioning function, without having either the undesirable flexibility of the sheet metal forming the casings, and without complicating production of the plate H.

It is a feature of the described construction that the rear edges of the two plates K are stressed away from each other by the inner casing, when the latter is properly tensioned, and said plates reacting to said 90 stress, pivot upon the bolts N and bear firmly at their front edges against the plate H. Thus there is established a tight joint between the plates K and the front plate H without bolting together or otherwise 95 positively connecting said plates. Thus as the fire-pot and combustion chamber expand and contract, there is nothing to restrict the plates K and H from undergoing the slight resulting relative movement, and no 100 breakage of said parts may result from such relative movement.

What I claim as my invention is:

1. In a furnace, a heater having projecting portions, forming passages respectively 105 in communication with the combustion chamber and ash-pit of the heater, inner and outer spaced casings about said heater, the outer casing having a gap therein, a terminal plate for said projecting portions hav- 110

- ing door openings in registration with said 5 passages, and closing said gap in the outer casing, and a pair of pivotally mounted plates formed separately from said casings and terminal plate and bearing against the lateral margins of said terminal plate and the vertical edges of the gap in the outer casing and vertical edges of the gap in the inner casing.
- 10 2. In a furnace, a heater having projecting portions, forming passages respectively in communication with the combustion chamber and ash-pit of the heater, inner and outer spaced casings about said heater, having registering gaps to accommodate 15 said projecting portions of the heater, a terminal plate for said projecting portions having door openings registering with said passages, said plate closing the gap in the outer casing, and a pair pivotally mounted plates, formed separately from the casings and terminal plate bearing against the lateral margins of said terminal plate and 20 engaging the inner and outer casings marginal to said gaps.
- 25 3. In a furnace, a heater having projecting portions forming passages respectively in communication with the combustion chamber and ash-pit of the heater, inner and outer spaced casings about said heater, the outer casing having a gap therein, a terminal plate for said projecting portions forming a closure for said gap in the outer casing and having door openings registering 30 with said passages, and a pair of pivotally mounted plates formed separately from said casings and terminal plate extending between said inner casing and the lateral margins of the terminal plate and the vertical 35 edges of the gap in the outer casing, said plates being flanged upon opposite sides to engage said inner casing and terminal plate.
- 40 4. In a furnace, a heater having projecting portions, forming passages respectively in communication with the combustion chamber and ash-pit of the heater, inner and outer spaced casings about said heater, said casings having gaps therein to accommodate 45 said projecting portions and door openings in registration with said passages for closing said gap in the outer casing, and a pair of plates formed separately from said casings and terminal plate extending from the lateral margins of said terminal 50 plate to the vertical edges of the gap in the inner casings, said plates being pivotally secured intermediate their ends to one of said projecting portions.
- 55 5. In a furnace, a heater having a combustion chamber and an ash-pit, projections extending from said heater and in communication with said combustion chamber and ash-pit, inner and outer spaced casings about said heater, the inner casing terminating short of said outer casing, the outer 60 casing having a gap therein, a terminal plate for said projecting portions having door openings in registration with said passages and closing said gaps in the outer casing, and a pair of pivotally mounted plates formed separately from said casings and terminal plate extending from the lateral margins of said terminal plate to the inner casing, said plates terminating at their lower ends in registration with the 65 lower edge of said inner casing.
6. In a furnace, a heater having a combustion chamber and an ash-pit, projections extending from said heater in communication respectively with said combustion chamber and ash-pit, inner and outer spaced casings surrounding said heater and having gaps to accommodate said projections, the inner casing terminating short of said outer casing and said ash-pit, a terminal plate 80 for said projections for closing the gap in the outer casing, said plate having door openings respectively registering with said extensions, a pair of vertically elongated plates extending from the lateral margins 85 of said terminal plate to said inner casing and means for pivotally connecting said plates to one of said projections.
7. In a furnace, a heater having projecting portions, forming passages respectively in communication with the combustion chamber and ash-pit of the heater, inner and outer spaced casings about said heater, said casings having gaps therein to accommodate 90 said projecting portions and door openings in registration with said passages for closing said gaps in the outer casing, and a pair of pivotally mounted vertically elongated plates secured to the inner casing at the vertical edges of the gaps therein, 95 said plates being formed separately from said casings and terminal plate and bearing against the lateral margins of said terminal plate and the vertical edges of the gap in the outer casing.
8. In a furnace, a heater having projecting portions forming passages respectively in communication with the combustion chamber and ash-pit of the heater, inner and outer spaced casings about said heater, 100 having registering gaps to accommodate said projecting portions of the heater, a terminal plate for said projecting portions having door openings registering with said 105 passages, said plate closing the gap in the outer casing, and a pair of vertically adjustable pivotally mounted plates formed separately from the casing and terminal plate bearing against the lateral margins of said terminal plate and engaging the inner 110 and outer casings marginal to said gaps.
9. In a furnace, a heater having projecting portions forming passages respectively in communication with the combustion chamber and ash-pit of the heater, inner 115

and outer spaced casings about said heater, the outer casing having a gap therein, a terminal plate for said projecting portions having door openings in registration with 5 said passages and closing said gap in the outer casing, a pair of plates formed separately from said casing and terminal plate secured to said inner casing and bearing

against the lateral margins of said terminal plate and the vertical edges of the gap in 10 the outer casing, and means for pivotally connecting said plates to one of said projections.

In testimony whereof I affix my signature.

HARRY L. WOOD.
